UNITED STATES PATENT OFFICE

2,130,637

VACUUM SEALING CAN

Frank L. Darling, Douglaston, N. Y., assignor, by
mesne assignments, to Crown Can Company,
Philadelphia, Pa., a corporation of Pennsyl-
vania

Application November 15, 1935, Serial No. 50,019

1 Claim. (Cl. 220—44)

My invention relates to certain new and useful improvements in cans for packing coffee, malted milk and other food products.

The present invention is a modification of the generic invention disclosed in my application Serial No. 20,838, filed May 10, 1935, and it has for its principal object to provide for the use of a vulcanized soft rubber elastic sealing ring or rings as the sealing element.

10 Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claim, reference being had to the accompanying drawing, in which:—

20 Figure 1 is a detail vertical cross section on the line 1—1 of Figure 2.

Figure 2 is a top plan view of a can embodying the invention.

25 Figure 3 is an enlarged detail view showing the plug-closure about to be pressed down.

Figures 4 and 5 are similar detailed views of modified forms of the invention.

In the drawing, in which like numerals and letters of reference indicate like parts in all the 30 figures, 1 represents the can and 2 the seam between the can 1 and its top 3.

The top 3 has a filling opening which is bounded by an upwardly and outwardly flared flange 5. Surrounding the flange 5 and spaced from it 35 is an upstanding bead 4, that portion of the top 3 between the flange 5 and the bead 4 serving as a seat against which the annular supporting portion 9 of the plug-type closure 6 rests in order to prevent contact between the cut edge of the 40 flange 5 and the crown 8 of the closure 6 when the closure is forced into place.

The closure 6 includes an annular wall 7 which merges with the crown or upstanding bead 8. The bead 8 serves as a cover for the flange 5 and 45 also has a seat or stop for the sealing ring 13, or rings 13b and 14 (see Figure 5) as the case may be.

The outer edge of the closure is extended upwardly and outwardly in order to provide a rim 50 12, from the extreme edge of which, at suitable intervals, extend points 10 which overlie the bead 4 and are spot-secured thereto as at 11, as in my former application aforesaid.

The flange 5, making an angle with the wall 55 7, provides a V-shaped pocket 15 into which the

sealing ring 13 projects. The ring 13 may be a rubber band of suitable dimensions and may be cut from a rubber tube if desired. In addition to the ring 13 a second ring 14 of elastic rubber or of plastic may be used to overlie and receive the cut edge of the flange 5b, as shown in Figure 5.

In Figures 4 and 5 are illustrated modified forms of the invention. In Figure 4 those parts which correspond in purpose or function to those 10 of Figures 1 to 3, inclusive, bear the same reference numeral plus the index letter "a", while similar parts in Figure 5 bear the same reference numeral plus the index letter "b", so a detailed description of these figures is thought to be 15 unnecessary. In Figure 5, 10 designates the second rubber ring (or plastic substance, if such be used) that embeds or receives the cut edge of the flange 5b.

The stop 9b in Figure 5 prevents the insertion 20 of the plug-closure to such a distance as would permit the cut edge of the flange 5b to cut through the ring 14, or, in other words, to limit the insertion of the plug-closure so as to stop it before 5b can pass through 14.

25 With the construction shown and described, an elastic rubber ring can be placed around the wall 7 (7a or 7b) and as the closure is forced down the ring 13 will enter the V-shaped space 15 and be squeezed into tight sealing contact 30 with the flange 5 and wall 7, the suction, due to the vacuum in the can, serving to assist in drawing the ring 15 into tight sealing engagement (see Figures 1 and 4). The ring, being of soft vulcanized rubber, is of course deformable and 35 will be drawn or pressed down into the V-shaped space 15 to tend to completely fill it (see Figure 5, for example).

The annular stop 9, as before intimated, serves to prevent the plug-closure from being forced 40 down too far and prevents the edge of the flange 5 from cutting through the sealing element 14, if such be used.

The present structure, while cheapening the manufacturing cost somewhat, possesses many of 45 the advantages of my previously designed can of the application aforesaid, in that it will effectively hold the vacuum and will be self-venting upon generation of pressure within the can.

If desired, in the manufacture of the can, the 50 plug wall 7 may be slightly tapered to permit the cut ring 13 to be easily placed on or slipped on, and furthermore the tapering will assist in the pressing of the plug into the can. The rings 13, if cut from tubing, will be very cheap to manu- 55

facture and the expense of molding or squirting a plastic compound into the crown **8** (or **8a** or **8b**, as the case may be) is avoided.

It should of course be understood that the **5** points **10** are secured to the can lightly, as in my previous application, so that they will become detached on the generation of dangerous pressures within the can and yet hold for ordinary pressures to allow the plug-closure itself to act **10** as a valve for venting purposes.

From the foregoing description, taken in connection with the accompanying drawing, it is thought that the complete construction and advantages of the invention will be clear to those **15** skilled in the art to which it relates.

What I claim is:

In a can having a filling opening bounded by an upwardly and outwardly flared flange, a plug-type closure fitting into said opening, and having **20** an annular upstanding wall merging with an annular crown portion which overlies said flange on the can, said flange and said annular upstanding wall providing between them a space

having, in cross-section, substantially the outline of an acute angle, and a rubber elastic sealing ring on said upstanding wall and adapted to be entirely positioned between said flange and said wall to form a seal when the closure is in place, the outer surface of said sealing ring being adapted to contact with said flared wall in such closed position, means to arrest the insertion of said closure before the edge of said flange can touch said crown portion, said closure having **10** points adapted to be secured to the can and by virtue of which the closure itself may act as a pressure relief valve, the movement of said sealing ring within said acute-angle space upon closing movement of the closure causing said **15** sealing ring to be wedged and entirely seated between said upstanding wall and said flared flange, and upward opening movement of said closure with said sealing ring thereon resulting in establishing a vent between said sealing ring **20** and said flared flange.

FRANK L. DARLING.
